UNITED STATES PATENT OFFICE.

ALBERT A. MILLER, OF WELLSBURG, WEST VIRGINIA, ASSIGNOR TO EAGLE MANUFACTURING COMPANY, OF WELLSBURG, WEST VIRGINIA, A CORPORATION OF WEST VIRGINIA.

CONTAINER.

Application filed August 23, 1921. Serial No. 494,455.

To all whom it may concern:

Be it known that I, ALBERT A. MILLER, a resident of Wellsburg, in the county of Brooke and State of West Virginia, have invented a new and useful Improvement in Containers, of which the following is a full, clear, and exact description.

The present invention relates broadly to shipping and storing vessels and more particularly to containers of this character for oil and similar liquids.

An important object of the present invention is to provide a container of this character adapted to effectively prevent leaking or spilling of the liquid contents therefrom.

Another object of the invention is to provide a container of such construction that leakage therefrom during periods of non-use is prevented by utilizing an ordinary cork, or other resilient closure, without the necessity of using any sealing cement or compound.

Still another object of the invention is to provide a container of this character having a neck with a screw-threaded portion for the usual spout and a smooth outwardly flaring portion of sufficient depth for an ordinary resilient sealing closure, the screw threads being effective for tightly drawing such closure into position.

A further object of the invention is to provide a container of the character referred to which may be economically and expeditiously manufactured.

The foregoing and other objects of the present invention, together with their attendant advantages, will be apparent as the invention becomes better understood by reference to the accompanying specification and drawings, forming a part thereof, it being premised that changes may be made in the various details and the manner of operation within the scope of the appended claim, without departing from the spirit of the invention.

In the drawings—

Figure 1 is a side elevation partly broken away of a container constructed in accordance with the present invention and having a sealing closure in position therein; and

Figure 2 is a similar view of the container with the spout in position therein.

The present invention provides a container which overcomes the difficulty experienced by all shippers of oil and other

liquids in containers taking a detachable screw-spout.

Heretofore, in containers of this character, it has been practically impossible to provide a neck closure, capable of preventing leakage of oil from the container. Attempts have been made to overcome this leakage by providing an ordinary cork or other closure forced into the screw-threaded portion of the neck and sealed in position with cement or paraffine. This method has been objectionable by reason of the unsightly appearance of the container when so sealed, the difficulty of removing the cork, and the liability of breaking particles of the cork, cement or paraffine and dropping the same into the interior of the container during removal of the closure. It is also old in constructions of this general character to provide a separate metallic screw plug or cap adapted to be screwed into position in or on the neck of the container when the same is not being used, or when it is being shipped, but this method is objectionable due to the increased cost and the necessity of manufacturing an extra closure other than cork or the like.

By the present invention, the objectionable tendencies and features of the methods heretofore in use are overcome.

Referring more particularly to the drawings, a container constructed in accordance with the present invention comprises a body portion 1, of any desired configuration, having the usual outlet neck for the contents thereof. In the present construction, this neck is formed with a lower screw-threaded portion 2 adapted to engage the ordinary detachable spout generally used with oil containers, and an upper smooth outwardly flaring portion 3. During non-use of the container, there may be inserted in the neck thereof a resilient closure 4 of cork or the like adapted to seat firmly against the smooth portion of the neck and form a sealing closure for the container. By slightly rotating the closure after it is in position, the screw threads will be effective for pulling the same more closely into sealing engagement with the smooth portion, thereby effectively preventing any leakage of the contents and preventing the closure from working loose.

When it is desired to use the container, the closure may be removed by simply un-

screwing the same and then withdrawing it after which the ordinary spout 5 is screwed into position.

By properly proportioning the length of the screw-threaded portion and the smooth portion, it has been found that the smooth portion does not interfere with the use of spouts as heretofore constructed.

The present invention eliminates entirely the use of a separate screw plug or cap and also the use of any sealing preparation. It provides for the use of a resilient sealing closure which may be procured very eco-

nomicly, thereby presenting many advantages over constructions at present in use. 15

I claim:

A sheet-metal container having a detachable spout, said container comprising a neck provided with a relatively smooth outwardly flared portion for co-operation with a sealing closure and a screw-threaded portion for co-operation with the closure and spout, substantially as described. 20

In testimony whereof, I have hereunto set my hand.

ALBERT A. MILLER.
